UNITED STATES PATENT OFFICE.

AUGUST SENNE, OF NEWARK, NEW JERSEY.

DESIGN FOR LADIES' SATCHEL.

Specification forming part of Design No. 5,232, dated August 22, 1871.

To all whom it may concern:

Be it known that I, AUGUST SENNE, of Newark, in the county of Essex and State of New Jersey, have invented a new and original Design for a Ladies' Satchel; and I do hereby declare that the following is a full, clear, and exact description thereof, which will enable others skilled in the art to make and use the same, reference being had to the accompanying drawing forming part of this specification.

Figure 1 of the photograph is a perspective view of my new satchel, showing it closed. Fig. 2 is a perspective view of the same, showing it opened.

Similar letters of reference indicate corresponding parts.

This invention relates to a new form of ladies' satchel.

The satchel A is made of two semi-oval pieces, A and B, hinged together at the lower and provided with suitable locking devices at the upper end.

I claim as my invention—
The design of the oval satchel, as shown.

AUGUST SENNE.
